US0D1056307S

(12) **United States Design Patent** (10) **Patent No.:** **US D1,056,307 S**
Chen (45) **Date of Patent:** **** Dec. 31, 2024**

(54) **CEILING LIGHT**

(71) Applicant: **E. MISHAN & SONS, INC.**, New York, NY (US)

(72) Inventor: **Qinan Chen**, Zhejiang (CN)

(73) Assignee: **E. MISHAN & SONS, INC.**, New York, NY (US)

(**) Term: **15 Years**

(21) Appl. No.: **29/885,447**

(22) Filed: **Feb. 24, 2023**

(51) LOC (14) Cl. **26-05**

(52) U.S. Cl.

USPC **D26/89**

(57) **CLAIM**

The ornamental design for a ceiling light as shown and described.

DESCRIPTION

FIG. 1 is a top, front perspective view of a ceiling light showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

In the drawings, the broken lines show portions of the ceiling light that form no part of the claim.

1 Claim, 5 Drawing Sheets
